US0D1039977S

(12) **United States Design Patent** (10) **Patent No.:** **US D1,039,977 S**
(45) **Date of Patent:** ** *Aug. 27, 2024

(54) **BOTTLE**

(71) Applicant: **The Procter & Gamble Company**,
Cincinnati, OH (US)

(72) Inventor: **Muthuraja Subbiah**, Singapore (SG)

(73) Assignee: **The Procter & Gamble Company**,
Cincinnati, OH (US)

(*) Notice: This patent is subject to a terminal disclaimer.

(**) Term: **15 Years**

(21) Appl. No.: **29/851,889**

(22) Filed: **Sep. 1, 2022**

CLAIM

The ornamental design for a bottle, as shown and described above.

DESCRIPTION

FIG. 1 is a perspective view of a bottle;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom view thereof.

The broken lines in the drawings depict portions of the bottle that form no part of the claimed design.
